LADDER

Manuel A. Nunes, Santa Clara County, Calif.

Application June 23, 1934, Serial No. 732,067

1 Claim. (Cl. 228—59)

In using ladders, particularly the tall ladders commonly used by fruit pickers and having the two side rails and a pivotally mounted leg, and from six or seven feet to twenty feet in length, they are subjected to stresses and strains that tend to weaken the joints between the several parts and thereby permit swaying or lateral movement of the ladder top when a weight is disposed thereon. This is particularly true of the joint between the stiles and the top tread or ladder head. In placing a ladder in position in an orchard invariably one stile will settle a little farther into the ground than the other, with the result that when a man climbs upwardly to the upper portion of the ladder an undue portion of his weight is thrown upon the one stile, and in the attempt of the ladder elements to adjust themselves to this unequal distribution of weight a general racking of the structure is effected. After a ladder has been subjected to this treatment a few times the joints become so loosened that the upper end will sway under a weight even though the ladder rest upon a level and solid surface, and of course such a ladder is not safe for orchard use.

It is the object of my invention to provide a means for positively and effectually eliminating all relative movement between the ladder stiles and their connecting treads.

It is also an object of the invention to provide a means of the character indicated that will be economical to manufacture, quickly and easily applied to new and old ladders, or ladders already in use, and that will be strong, durable, and highly efficient in its practical application.

In the drawing:

Figure 1 is a front elevation of a portion of a ladder embodying my invention.

Figure 2 is a plan view of a portion of the same.

Figure 3 is a front elevation of another portion of a ladder embodying my invention.

In carrying out my invention as herein disclosed, I show at 1 a portion of one ladder stile with the top tread or head showing at 2. The part 3 is a metal band encompassing the stile 1. The upper end of the stile is let into the under side of the top 2 as indicated at 4.

At 5 is shown a rod or bar disposed at an angle of forty-five degrees to the stile 1 and having end portions as 6 and 7 bent to form obtuse angles with the main portion and disposed to pass at right angles through the stile and head and from their inner sides as shown.

The end 6 passes through a plate 8 disposed

lengthwise of the head 2 on the under side thereof, and is threaded to receive a nut 9. When the nut 9 is tightened up the main portion of the rod is seated tightly against the plate 8.

The end portion 7 is threaded as at 10 to receive a nut 11 which is threaded thereon to seat tightly against the main portion as at 12. This end portion passes completely through the stile and is fitted with a nut 13. In this case the band 3 takes the place of washers, plates, etc., and the nuts 11—13 seat directly thereon. When the nut 13 is tightened up it draws the rod snugly into place, and this fastening cooperates with the connection at 9 to lock the stile 1 in fixed position relative to the head 2, and no swaying or giving of the ladder can take place even though it may be placed on loose and uneven ground, or subjected to a heavy load on its upper portion.

In Figure 3 a form of the invention is shown wherein a support and brace is inserted between the stile and one of the steps of the ladder. In this case the rod 14 is disposed above the step instead of underneath it as in the case of rod 5, and consequently is subjected to tensional strains. The end 15 passes through stile 1 and plates 16—17 and is threaded to receive nuts as 18 and 19. The end 20 passes downwardly through step 21 and plates 22—23, and is threaded to receive a nut 24.

While a single rod or brace has been described in connection with each of the embodiments disclosed, the desired results are obtained by providing each of these braces in pairs. The rod 5 is spaced back a little from the front edge of the stile and top, while a duplicate rod 5a is disposed an equal distance from the back edge of the stile. A rod 14a is similarly disposed relative to rod 14.

An important feature of the invention is the disposition of the plate 8. Since brace rods 5 and 5a are placed in both of the angles formed by the two stiles and a tread, it follows that the ends 6—6a of the other two brace rods 5—5a are also passed through the plates 8—8a with the result that when the nuts 9—9a are tightened up the plates 8—8a function as links that tie the two rods 8 together and the two rods 8a together and prevent their working into the substance of the wood. The provision of this tie plate or link is an essential feature in the present invention since it provides a positive means for preventing relative movement of the rods to which it is connected.

It is to be understood, of course, that while I have herein shown and described but two spe-

cific embodiments of the invention, changes in form, construction, and method of assembly and application may be made within the scope of the appended claim.

5 I claim:

The combination with the stiles of a ladder and the connecting tread or cross member, of brace means disposed across the opposing angles

formed by the stiles and tread, a tie plate disposed on the tread and longitudinally thereof, one end of each brace means passing through the tie plate and tread and the other end passing through an adjacent stile, and fastening means on each end of each brace means disposed to engage the tread and stiles respectively.
